US0D1009002S

(12) **United States Design Patent** (10) **Patent No.:** **US D1,009,002 S**
(45) **Date of Patent:** **** Dec. 26, 2023**

(54) **REMOTE CONTROLLER**

(71) Applicant: **Shan Xu**, Huizhou (CN)

(72) Inventor: **Shan Xu**, Huizhou (CN)

(73) Assignee: **HUIZHOU WISVA
OPTOELECTRONICS CO., LTD.**,
Huizhou (CN)

(**) Term: **15 Years**

(21) Appl. No.: **29/903,429**

(22) Filed: **Sep. 22, 2023**

(51) LOC (14) Cl. **14-03**

(52) U.S. Cl.

USPC **D14/218**

(58) **Field of Classification Search**

USPC D14/218, 349, 480.5; D13/168, 173,
D13/162, 162.1, 166, 171, 174

(57) **CLAIM**

The ornamental design for a remote controller, as shown and described.

DESCRIPTION

FIG. 1 is a perspective view of a remote controller showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1 thereof.

The broken lines showing portions of the remote controller illustrate portions of the article, and form no part of the claimed design. The dot-dash broken lines indicate where the enlargements have been taken, and form no part of the claimed design.

1 Claim, 9 Drawing Sheets
